UNITED STATES PATENT OFFICE.

AUGUSTUS T. BROOK, OF NEW YORK, N. Y.

WIRE POST.

SPECIFICATION forming part of Letters Patent No. 658,889, dated October 2, 1900.

Application filed November 9, 1899. Serial No. 736,372. (No model.)

To all whom it may concern:

Be it known that I, AUGUSTUS TORBERT BROOK, residing at the city of New York, State of New York, have invented certain 5 new and useful Improvements in Wire Posts, of which the following is a description, referring to the accompanying drawings, which form part of this specification.

The invention relates particularly to wire 10 posts or pickets for wire fences, though its use is not necessarily restricted to these purposes.

The object of the invention is to produce an 15 extremely cheap, simple, durable, and effective post.

The post is designed to be used at intervals 20 to support horizontal fence-wires. At much longer intervals strong wooden or other posts can be used, in which case the wire posts of 25 my invention can be made proportionally lighter.

Briefly stated, the improved post in its most preferred form consists of a single piece of rod or wire bent back upon itself to form the 25 top of the post and then twisted together. From twelve to eighteen inches from the bottom of the post a flat plate is placed between the two portions of the wire, and at the foot 30 of the post the two ends of the wire are made fast to the horizontal anchor-plate by being passed through holes in the plate, then lapped back upon themselves and suitably fastened.

The invention is of so simple a nature that 35 it can be readily understood by an inspection of the accompanying drawings, wherein—

Figure 1 shows the post in use, the ground in which it is anchored being shown in section. Fig. 2 shows, in enlarged scale, the details of the lower portions of the post.

While I prefer to make the post of a single 40 wire bent back upon itself at the top to form an eye and twisted together throughout the length of the post, two or more wires may of course be used. For the purposes of description I will speak of each of the ends of the 45 wire or wires as though it were a separate wire.

To anchor the foot of the post firmly in the ground, I provide a plate *a*, having preferably four holes *h*. Two wires *w* extend down 50 through two of the holes and are then bent around and brought upward through the other holes and twisted around, so as to secure the post firmly to the plate *a*, as shown in the figures. While this plate *a* anchors the post 55 firmly in the ground, so that it cannot be readily pulled upward, it does not prevent the post working sidewise under the strains exerted by the wind or by any other cause upon the fence. Such working of the post in 60 the ground is apt to loosen the post, and for the purpose of anchoring the post against such lateral movement I provide a section-plate *p*, which when in use is a few inches below the surface of the ground, as seen in 65 Fig. 1. This plate *p* is preferably notched, as at *n*, and the wires *w* are twisted tightly together, embracing the plate *p* in a line between the notches *n*, as best seen in Fig. 2. Where the wires *w* are parts of a single wire 70 bent at the top of the post to form a loop *l*, a very simple, but ornamental effect is produced. The fence-wires *f* are preferably secured to the post by small binding wires or staples *s*, as in Fig. 1. 75

The features which I claim as new and characteristic of my invention are as follows:

A fence-post consisting of a single length of wire forming a loop at the top of the post and twisted together substantially from end 80 to end, a vertically-disposed plate *p* embraced by the twisted wire or wires, and a horizontal anchor-plate having holes through which the two ends of the wire are looped, said ends being twisted and so secured, substantially as 85 set forth.

Signed this 20th day of October, 1899, at New York, N. Y.

AUGUSTUS T. BROOK.
